UNITED STATES PATENT OFFICE.

ARTHUR L. REMINGTON, OF FITCHBURG, MASSACHUSETTS.

DESIGN FOR A METAL BLADE.

SPECIFICATION forming part of Design No. 37,302, dated January 24, 1905.

Application filed May 23, 1904. Serial No. 209,383. Term of patent 14 years.

To all whom it may concern:

Be it known that I, ARTHUR L. REMINGTON, a citizen of the United States of America, and a resident of Fitchburg, in the county of Worcester and Commonwealth of Massachusetts, have invented a new, original, and ornamental Design for Metal Blades, of which the following is a specification, reference being had to the accompanying drawing, forming a part thereof, wherein is shown the ornamental

design on an enlarged scale applied to the side of a portion of a blade.

What I claim as new, and desire to secure by Letters Patent, is—

The ornamental design for a metal blade as herein shown. 15
